UNITED STATES PATENT OFFICE.

AUGUST SWEDBERG, OF KINGSTON, PENNSYLVANIA.

HOLDER FOR STROPPING SAFETY-RAZOR BLADES.

1,162,888.

Specification of Letters Patent.

Patented Dec. 7, 1915.

Application filed August 5, 1915. Serial No. 43,806.

To all whom it may concern:

Be it known that I, AUGUST SWEDBERG, a citizen of the United States, residing at Kingston, in the county of Luzerne and State of Pennsylvania, have invented certain new and useful Improvements in Holders for Stropping Safety-Razor Blades, of which the following is a specification, reference being had to the accompanying drawings.

This invention relates to means for holding blades of safety razors while they are being stropped or honed; and the primary object of the invention is the provision of a very simple, cheaply-made, easily applied and effective holder, so constructed that a safety razor blade may be securely and firmly clamped within the holder and cannot become detached therefrom by accident.

The invention is illustrated in the accompanying drawings, wherein:

Figure 1 is a plan view of my blade holder, the handle being partly in section; Fig. 2 is a longitudinal sectional view of the handle with the blade holder inserted therein; Fig. 3 is an elevation of the blade holder; Fig. 4 is a rear view of the handle showing in dotted lines the tangs 10 compressed; Fig. 5 is a front end view of the handle; Fig. 6 is a cross sectional view on the line 6—6 of Fig. 1.

Referring to these figures 2 designates a handle which may be made of wood, metal, celluloid, or any other suitable material and which is formed with a longitudinally extending bore 3 which opens upon the ends of the handle. At its forward end the handle is reinforced by the ferrule 4 and by an interior reinforcing bushing 5. This bushing defines a rectangular opening and is so formed as to provide the oppositely disposed stop shoulders 6. The opposite end of the handle is formed with a bushing 7. The blade-engaging member comprises a strip 45 of metal bent upon itself, as at 8, to provide oppositely disposed parallel clamping jaws 9. The outer faces of these jaws are transversely rounded and the inner faces of the jaws are flat to engage flat against a razor blade A. It will be seen from Fig. 3 that the strip from which the jaws 9 are formed is of a resilient material and as a consequence the jaws are resiliently forced apart. As illustrated in Fig. 1, each of these jaws 55 has extending from it the relatively narrow tang 10 having a length slightly greater

than the length of the handle 2 and formed at their ends with the stop shoulders or heads 11. The tangs 10 being narrower than the jaws 9 provide the shoulders 12.

In order to use my stropping device the razor blade A is inserted between the jaws or members 9. The tangs are then compressed so as to hold the jaws securely in engagement with the blades and the headed ends of the tangs are then inserted through the bushing 5 and the tangs forced backward until the heads 11 snap behind the bushing 7. It will be observed that the bushing 5 defines a relatively narrow rectangular opening while the bushing 7 defines a relatively wide opening. The bushing 5 holds the jaws tightly closed against each other and against the blade, while the bushing 7 permits the ends of the tangs to spring apart, and holds the heads in locked engagement with the bushing as illustrated in Fig. 2.

The shoulders 12 bear against the seats 6 formed in the bushing 5 so that the clamping portion of the device is firmly held upon the handle and cannot shift relative thereto, at the same time the blade is firmly clamped between the jaws without the necessity of providing the jaws with projections to engage the blade. Thus in the blade A illustrated, there are a number of perforations but the jaws clamp upon this blade so securely that there is no necessity of the bosses or projections upon the inner faces of the blades connecting through these perforations. It will be seen that the curved outer faces of the jaws 9 permit the holder to be rotated axially so as to bring the blade at a proper angle to the strop or hone. When it is desired to release the blade from the clamping jaws it is only necessary to press the headed ends of the tangs together so that the heads 11 will pass through the opening in the bushing 7 whereupon the jaws may be withdrawn. When withdrawn the jaws spring to the position shown in Fig. 3, thus permitting the ready removal of the blade.

As before stated, the bushing 5 defines a relatively narrow slot whose width is approximately the same as the thickness of the two jaws at their free ends when the jaws are closed tightly together. The heads 11 on the ends of the tangs have a width equal to the interior diameter of the circular bushing 7. As a consequence of this construction when the tangs spring

slightly apart as they will do after they are inserted in the handle and the heads have passed between the bushing, the heads will be disposed as in Fig. 4, and the shoulders 5 defined by the heads will engage over the end of the bushing 7. By forcing the heads 11 together, however, they are brought into a position of alinement with the axis of the bushing 7 and as they have a diameter 10 slightly less than this bushing they will pass freely through it.

My device is adapted to be used with almost every style of safety razor blade and wherever the blade is made of thin metal, 15 I have found it very effective in practice for the purpose of sharpening, honing, or otherwise treating razors, and may be very cheaply made and is readily operated.

Having thus described my invention, what 20 I claim is:

1. In a device for holding safety razor blades, a handle having a bore, a rectangular bushing disposed in one end of the handle defining a relatively narrow entrance slot communicating with said bore, and a blade clamping device comprising a strip of resilient material bent upon itself to provide oppositely disposed normally divergent resilient clamping jaws, the strip being extended from said jaws to provide elongated tangs having a length slightly greater than the length of the handle, each tang being provided at its extremity with a head.

2. In a device for holding safety razor blades, a handle having a bore, a rectangular bushing disposed in one end of the handle

defining a relatively narrow entrance slot communicating with said bore, and a blade clamping device comprising a strip of resilient material bent upon itself to provide 40 oppositely disposed normally divergent resilient clamping jaws, the strip being extended from said jaws to provide elongated tangs having a length slightly greater than the length of the handle, each tang being 45 provided at its extremity with a head, the width of the head being equal to the bore at the rear end of the handle.

3. A holder for safety razor blades comprising a handle formed with a longitudinally extending bore, one end of the handle being formed to provide a relatively narrow slot communicating with the bore and the other end of the handle being formed to provide a circular opening communicating with the bore, and a blade clamping device coacting with the handle comprising oppositely disposed confronting jaws resiliently connected to each other at one end and normally divergent with relation to each other, 60 each of said jaws at its free end being extended to form a tang having a length equal to the handle, the end of the tang being formed with a head, each of said heads having a width equal to the diameter of the circular bore at the rear of the handle.

In testimony whereof I hereunto affix my signature in the presence of two witnesses.

AUGUST SWEDBERG.
